PROTOTYPE FOR GAUGING THE CONTOUR
OF AN OPENING FOR USE AS A GUIDE IN
CUTTING A CLOSURE THEREFOR

Leo Bernitz, Albuquerque, N. Mex.

Application May 14, 1951, Serial No. 226,166

8 Claims. (Cl. 144—2)

1

The present invention relates to a prototype for gaging the contour of an opening for use as a guide in cutting a closure therefor.

One object of the present invention is to provide, in a device of the character described, improved means which permit the adjusting of the pattern device or prototype to the size of an opening to be closed and subsequently cutting the closure to fit said opening from the form thus provided.

Another object of the present invention is to provide a device of the above stated character equipped with cutting means which will provide the desired bevel on the door or other object being cut for an opening.

Another object of the present invention is to provide a device which can be more quickly and accurately adjusted for measuring and subsequently cutting a door or other object so that it may be more quickly and accurately fitted to, and hung within a frame or opening.

Still another object of the present invention is to provide a device of the character described affording means whereby the door or other object may be fitted, cut and hung with exacting accuracy within its opening with a considerable saving of time and by a single workman without the aid of an assistant.

Yet another object of the present invention is to provide a device of the character described which can be so adjusted as to provide the necessary clearance for the door or other object which is to be fitted and hung.

Still another object of the present invention is to provide a device of the character described which is more efficient in operation and yet simple in construction and economical to manufacture.

With the above and other objects in view as will appear as the description proceeds, the invention resides in the novel construction, combination and arrangement of parts, as herein-after more specifically set forth, claimed and shown in the accompanying drawings which form a part of this application for Letters Patent.

In the accompanying drawings are illustrated preferred and practical embodiments of the invention, it being understood, however, that the drawings are merely illustrative and that the inventive concept is susceptible of other embodiments and utilizations, and that the illustrated embodiments likewise are susceptible of a wide range of variation and modification without departing from the spirit of the invention or the scope of the appended claims.

2

In said drawings,

Fig. 1 is a front elevation illustrating the device of the present invention as used in connection with a framed-in-door opening;

5 Fig. 2 is a side elevational view of the device per se;

Fig. 3 is an enlarged, vertical section through one of the adjusting units located at the mid-width of the device;

10 Fig. 4 is an enlarged detail view in elevation of one of the adjusting means for the top rail structure;

Fig. 5 is an enlarged horizontal cross sectional detail on line 5—5 of Fig. 1;

15 Fig. 6 is a fragmentary end view of the prototype with the cutting device in its operative position;

Fig. 7 is a top plan view of the device shown in Fig. 6 with the prototype omitted;

Fig. 8 is a bottom view of the structure shown in Fig. 6.

Referring now in detail to the drawings and first advertising to Figs. 1 to 5 inclusive, the reference numeral 1 has been used to generally designate the frame of this new and improved measuring or fitting device embodying the present invention. This invention has been described in conjunction with the fitting, measuring, cutting and hanging of doors in door frames or

20 jambs, and it is to be understood that this has been done in order to facilitate the description of the present invention, and has been done by way of illustration and not by way of limitation. The measuring or fitting device of the present

25 invention may be made from any desired material, such as, for example, wood, metal, plastic, hard rubber or any other suitable material and it may be made so that it may be adjusted to any desired shape or size so as to be fitted within a variety of different sized openings. This measuring or fitting device has at each side an outwardly and inwardly adjustable side bar structure comprising an inner bar 5 and an outer bar 6; and a vertically adjustable top rail structure

30 40 45 50 55 9, suitably secured to the frame 1 as shown most clearly in Figs. 1 and 2. It will be readily seen and understood from this arrangement that the movable side and top structure may be changed into a variety of sizes and shapes so as to fit a multiplicity and variety of openings varying in contour.

In order to take care of various irregularities of contour in the borders of the openings to be gaged, the adjustable side bars 5 and 6 at each side of the device are spaced apart from each

other by the spacing means 8, as clearly shown in Fig. 1. The bar members 5 and 6 may be connected together by suitable threaded means 16 passing through and secured to a nut 7 as is shown most clearly in Fig. 5. This arrangement permits the outside bar 6 to be moved the necessary distance away from the inside bar 5 by flexing it so as to fit any irregularities in the door frame 17, or to fit an opening bordered by warped timbers. The inside bar members 5 are adjustably connected to the frame member 1 by any suitable means, such as, for example, the threaded rod members 4 which may pass into correspondingly threaded tube members 3, the said threaded tube members 3 being suitably secured to a post 2 and the sides of the frame 1 by any suitable securing means, as is shown most clearly in Figs. 1 and 3. This arrangement provides for lateral movement of the bars 5 and 6 toward or away from the frame 1 as may be necessary in order to fit the opening in which the door is to be hung. The three posts 2 carried by the midwidth portion of the frame are all directed lengthwise of said frame, and therefore, do not project objectionably from its face. Each screwthreaded rod 4 has one of its end portions passing loosely through a smooth bore for it in a said post, while the opposite outer end portion of the bar is non-turnably secured to the adjacent rail 5 and spacer 8. As already alluded to, each of said rods 4 is in a screwthreaded relation to an aforesaid sleeve 3 which surrounds it, the outer end of said sleeve loosely abutting a side of the adjacent post; hence the workman, by rotating said sleeves can adjust said rods as desired and thereby adjust bodily the pair of bars 5 and 6, at the sides of the frame. In Fig. 2 the ends of pairs of bolts 35 appear in the rail 6. In the assembled structure, at each side of the frame each said pair of bolts extends into the underlying spacer 8, thus securing said spacers to said bars.

The top member or rail 9 is fitted over a carrying member 10, as is shown most clearly in Figs. 1 and 4. The member 10 which carries the top rail 9 is movably secured to the frame 1 by any suitable means, such as, for example, the threaded rod 11 which passes through a correspondingly threaded nut 12, down through the frame 1 where it terminates in a second threaded nut 15. If desired, a suitable spring member 13 placed between the frame projection 1 and the washer 14 on the nut 15, may provide suitable loading to maintain the top rail 9 in the correct measuring position, as is shown most clearly in Figs. 1 and 4. The provision of a pair of these adjustments, one on each end of the carrying member 10, affords means for adjusting to any opening, even if the opening is irregular or slanting. The provision of a removable top rail 9 carried by the carrying member 10 provides means for easily and quickly changing the size or shape of the top rail 9, as desired, in order that a wide variety of shapes and sizes of openings may be measured.

The operation of the new and improved measuring or fitting device of the present invention is quite simple. The frame member 1 is first placed in the opening to be measured or fitted, between the door framing members 17 as is shown most clearly in Fig. 1. The side bars 5 and 6 are then moved outwardly by means of the screw adjusting means 2, 3 and 4 until the outer bar 6 touches the sides 17 of the opening to be measured or fitted. Considerable crooked-

ness or warping in the timbers 17 may then be gaged by means of the adjusting means 7 and 16 located between the side bars 5 and 6, so that an absolutely accurate fit may be obtained. 5 This gaging operation is effected by turning the nut 7, together with the reversely screwthreaded end portions of the rod 16 so that the latter will bow the resilient bar 5 to conform to the warped surface it engages or conforms to. By the aforesaid adjusting means both a simple and compound outward bowing of the side portions of the prototype can be effected. The top rail 9 is then moved upwardly to fit against the top of the opening in the frame 17, by means of the 10 adjusting means 11, 12, 13, 14 and 15, as already described. Any irregularities, warping or crookedness in the top timber 17 of the door framing may be adjusted for by means of the 15 adjusting means 11, 12, 13, 14 and 15 so that an absolutely accurate fit may be obtained. When the proper adjustments have been made 20 the frame 1 and its accompanying parts may be removed from the opening and an absolutely accurate pattern for the door which is to be hung 25 is thus obtained.

Figs. 6, 7 and 8 show the cutting means designed to be used in conjunction with the measuring or fitting means previously described. The cutting means has been generally designated by the reference numeral 23 and comprises essentially a driving means or motor 19 adjustably secured to a motor mount member 20, the motor mount member 20 being carried by a suitable flat plate member 21 to which the said motor mount member 20 is either suitably secured, or is made an integral part thereof, as desired. A suitable rotary cutter 23, is secured to the lower end of the downwardly extending shaft 22 of the motor 19 by any suitable means, such as, for example, the lock nut 24. If desired, a suitable guard means 25 may be secured to the bottom of the plate member 21 by the screw bolts 18, around the cutter 23, so as to protect the user from being accidentally cut while using the invention. A suitable adjustable guide member 26 is carried on the bottom of the plate member 21 to provide means for regulating the depth of cut. The motor 19 may be pivotally secured to the motor mount 20 by any suitable means, such as, for example, the bracket member 29 which may be securely affixed to the motor 19 by means of the bolts 28, as is shown most clearly in Fig. 6. The lower end of the bracket 29 may be pivotally secured to the motor mount 20 by any suitable means, such as, for example, the pivot pin 27. 45 Adjusting means, such as the adjustable screw bolt 30 at the top of the bracket member 29 provides for producing a bevel cut on the material by moving the motor shaft 22 away from the vertical, thus aiding in producing a bevel cut on the door which is to be hung, so that it may accurately fit the door opening.

The operation of the cutting device with the fitting or measuring device is relatively simple. 50 After the door opening has been accurately gaged by the fitting or measuring device as previously described, the fitting or measuring device is placed over the door which is to be hung. The cutting tool is then brought up to the work and placed over the fitting or measuring device as is shown most clearly in Fig. 6. The cutting guide member 26 is then adjusted for the proper depth of cut, and, if necessary, the motor 19 is tilted the proper amount by means of the adjustment screw 30, so as to provide a beveled cut, and the 55

guide member 26 is then moved along the edges of the fitting or measuring device and the door is then cut to the proper size after which it is ready to be hung and a perfect fit of the door or other object in the opening is thus obtained.

It will be observed that a rotary cutter is used in trimming the door, said cutter rotating about an axis which extends transversely of the plane in which the prototype lies, said cutter being adjustable to vary the inclination of its axis of rotation. Also from Figs. 6 and 8 it will be seen that the plate 24, which mediately carries the motor and cutter, is sufficiently long readily to be moved across the gaps at the corners of the prototype. Also owing to all the fasteners, bolts and operable parts of the prototype being located between the planes defined by the smooth outer side faces of the prototype, no obstacle is encountered by said plate when it is used in the manner already described; and the rotating cutter causes no objectionable vibration.

It is to be understood that the forms of the invention herein shown and described are to be taken as preferred and practical embodiments of the same, and that various changes may be made in the shape, size and arrangement of parts without departing from the spirit of my invention or the scope of the appended claims.

I claim:

1. In a device for shaping and dimensioning a closure to fit an opening, a substantially rectangular rigid frame comprising rightangularly joined top, bottom and side members, a rail carried by said top member and extending along the outer side thereof, adjustable means securing said rail to said top member and operable to maintain said rail in a variously spaced distance from said top member to gage the length of an opening while said frame is contained therein, a bar extending outwardly along a said side member of said frame, means carried by said frame to adjust said bar outwardly and inwardly in relation to said frame to gage the width of an opening while said frame is contained therein, said frame, together with said adjusted bar and rail, being superimposable upon a closure to guide a cutter, a flat plate movable along the upper face of the marginal portion of said frame, a guide member carried by said plate to travel along the edge portions of the sides and ends of said frame, and a rotating cutter mediately carried by said plate to trim said closure to fit an opening the size and contour of which has been gaged by the device in the aforesaid manner.

2. The subject matter of claim 1 and said adjustable means which attaches said rail to said top member comprising a projection carried by each end portion of said top member of said frame, and a rotatable screwthreaded rod carried by each of said projections and connected with the end portion of said rail at its side of said frame.

3. In a device for shaping and dimensioning a closure to fit an opening, a substantially rectangular rigid frame comprising rightangularly joined top, bottom and side members, a rail structure carried by said top member and extending along the outer side thereof, said rail structure comprising an inner and an outer part, adjustable means attaching the inner part of said rail structure to said top member and operable to maintain said rail structure in a variously spaced distance from said top member to gage the length of an opening while said frame is contained therein, the outer part of said rail struc-

ture being detachable from the inner part thereof so that outer rails of different lengths may be used in said rail structure, said frame, together with said rail structure, being superimposable upon a closure to guide a cutter moved exteriorly along the sides and ends of the device in trimming said closure to fit an opening the size and contour of which has been gaged by the device in the aforesaid manner.

10 4. In a device for shaping and dimensioning a closure to fit an opening, a substantially rigid frame dimensioned to be contained within the opening to be gaged with a clearance between a side portion of said frame and an adjacent inner side portion of the structure containing said opening, a resilient bar structure occupying said space and comprising two bars extending alongside each other and alongside said frame, means carried by said frame to adjust said bar structure as a whole outwardly and inwardly in relation to said frame, and means acting between said bars to bow parts of them outwardly from each other, thus to conform the outer bar to the contour of the adjacent part of the material

15 20 25 bordering an opening being gaged by the device.

5. The subject matter of claim 4 and said bar bowing means consisting of a rod having a turnable nut secured to it between said bars, said rod having at one side of said nut a right hand screw-

30 35 threaded engagement with one of said bars and at the opposite side of said nut a left hand screw-threaded engagement with the other of said bars.

6. A structure of the kind described comprising a generally rectangular prototype disposable 40 45 50 55 within a door opening and having adjustable marginal portions abuttable against the inner surface of said opening to gage its size and shape, the marginal portion of the upper face of said prototype presenting a flat, upwardly facing unobstructed surface when the prototype is placed upon a horizontally supported door to be trimmed, a plate, a motor mount member secured to said plate and upstanding rightangularly from one face thereof, a motor carried by said motor mount member, said motor comprising a drive shaft which extends down to a point below said prototype when the latter has been placed upon a door to be trimmed, a cutter of the rotary type carried by the lower end portion of said shaft and usable to trim the door as said plate is moved along the marginal portion of said prototype, and guide means carried by said plate and projecting downwardly therefrom in a position to be moved along the side and end edge of said prototype while the latter is overlying a door to be trimmed.

7. A structure of the kind described comprising a generally rectangular prototype disposable within a door opening and having adjustable marginal portions abuttable against the inner 60 65 70 75 surface of said opening to gage its size and shape, the marginal portion of the upper face of said prototype presenting a flat, upwardly facing unobstructed surface when the prototype is placed upon a horizontally supported door to be trimmed, a plate, a motor mount member secured to said plate and upstanding rightangularly from one face thereof, a motor spaced away from said member and having a lower end portion pivotally connected with the lower portion of said member to swing about an axis that extends parallel to said plate, horizontally adjustable means connecting the upper part of said motor with the upper part of said member so as to tilt said motor in relation to said member and plate, said motor comprising a drive shaft which extends down to

a point below said prototype when the latter has been placed upon a door to be trimmed, a cutter of the rotary type carried by the lower end portion of said shaft and usable to trim the door in a more or less beveled manner as said plate is moved along the marginal portion of the prototype, and guide means carried by said plate and projecting downwardly therefrom in a position to be moved along the side and end edge of the prototype while the latter is overlying a door to be trimmed.

8. In a device for shaping and dimensioning a closure to fit an opening, a substantially rigid elongated frame dimensioned to be contained within the opening to be gaged with a clearance between a side portion of said frame and an adjacent inner side portion of the structure containing said opening, a bar structure extending longitudinally of the frame and occupying said clearance, a plurality of longitudinally spaced apart posts carried by the midwidth portion of the frame, each of said posts extending lengthwise of the frame, a screw threaded rod associated with each of said posts, each of said rods having an inner end portion projecting loosely through the post with which it is associated and having an outer end portion connected with said

5

10

15

20

25

bar structure to adjust said bar structure inwardly and outwardly, and a tube member rotatably carried by each of said rods in a screw-threaded relation thereto, said tube members each loosely bridging the space between a said post and said bar structure, one end of each of said tube members abutting a said post and the other end thereof abutting a said bar structure so that rotation of each said tube member longitudinally adjusts the rod therewithin, thus effecting the aforesaid outward and inward adjustment of said bar structure.
